UNITED STATES PATENT OFFICE.

ISAAC N. DANN, OF NEW HAVEN, CONNECTICUT.

DESIGN FOR A CHAIR.

SPECIFICATION forming part of Design No. 23,008, dated January 16, 1894.

Application filed July 13, 1893. Serial No. 480,425. Term of patent 7 years.

To all whom it may concern:

Be it known that I, ISAAC N. DANN, a citizen of the United States, residing at New Haven, county of New Haven, and State of Connecticut, have invented and produced a new and original Design for Chairs, of which the following is a specification, reference being had to the accompanying drawing, forming part thereof.

10 The leading feature of my design consists in a chair having plain surfaced legs and standards, and transversely and longitudinally curved arms of an interwoven or basket-like appearance, and of greater width than the diameter of said legs and standards.

15 In the drawing, the letters *a a* designate the rear legs of the chair, *b b* the front legs, *c c* the rear standards, and *d d* the front standards, but one of the latter appearing in the drawing. Said legs and standards are bare, and as shown in the drawing have a plain surface except for the scroll ornamentation 2 at the upper ends of the standards *c* and at the lower ends of legs *b*. Between the standards *c c* are a series of panels 3 4 of open work, surmounted by a crown-piece 5 of closely interwoven basket-work.

20 The seat *e* is of interwoven basket work and extends from the rear to the front side of the chair by a regular curve, and at its front edge curves downwardly and rearwardly. The arms *f f* are also of interwoven basket-work, and extend from the rear standards *c c* by a regular curve, over the upper ends of the front standards *d*, and join the front legs *b b* at a point slightly below the plane of seat *e*. Said arms are curved transversely and are of a gradually increasing width from each end toward the center thereof. The space between the arms and the seat 30 and between the front and rear standards is occupied by panels 6 of open work.

Having thus fully described my design, what I claim, and desire to secure by Letters Patent, is--

40 The design for a chair substantially as herein shown and described.

ISAAC N. DANN.
